UNITED STATES PATENT OFFICE.

NORMAN LIPSKY, OF NEW YORK, N. Y., ASSIGNOR TO HALCOLITE COMPANY, INC., A CORPORATION OF NEW YORK.

DESIGN FOR A CANDLE CUP OR ARTICLE OF ANALOGOUS NATURE.

Application filed September 18, 1928. Serial No. 28,186. Term of patent 7 years.

To all whom it may concern:

Be it known that I, NORMAN LIPSKY, a citizen of the United States of America, and a resident of the city, county, and State of New York, have invented a new, original, and ornamental Design for a Candle Cup or Article of Analogous Nature, of which the following is a specification, reference being had to the accompanying drawing, forming a part hereof.

In these drawings:

Figure 1 is an inverted plan view of the

candle cup or article of analogous nature, the part shown in full line outline being ornamented in the same manner as the part more fully illustrated; and

Figure 2 is a diagrammatical side elevational view of the same.

I claim:

The ornamental design for a candle cup or article of analogous nature, substantially as shown and described.

NORMAN LIPSKY.
